UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

ELECTRIC-LIGHTING SYSTEM.

SPECIFICATION forming part of Letters Patent No. 316,708, dated April 28, 1885.

Application filed November 28, 1884. (No model.)

To all whom it may concern:

Be it known that I, EDWARD WESTON, a subject of the Queen of Great Britain, and a resident of Newark, in the county of Essex and State of New Jersey, have invented certain new and useful Improvements in Electric-Lighting Systems, of which the following is a specification, reference being had to the drawings accompanying and forming a part of the same.

In certain patents granted to the United States Electric Lighting Company as my assignee, September 9, 1884, Nos. 304,882, 304,883, and 304,884, I have shown and described a system of electric lighting in which incandescent lamps are run two or more in series in parallel or multiple circuits from two main conductors, and in which provision is made for preserving the continuity of each cross-circuit in case any number of lamps less than all in that circuit be extinguished, by substituting equivalent resistances for the lamps withdrawn; also, for interrupting the circuit through said resistances, or, in other words, breaking the cross-circuit when all lamps in the same are withdrawn. In another form of multiple-series distribution the line at certain points is divided into a number of branches, and the lamps are included, singly or in limited numbers, in each branch. A considerable number of such groups of derived circuits may be formed in the same line, the groups being in series. To this particular form of circuit my present invention relates, the object being to replace extinguished lamps or other like devices of any group by equivalent resistances, so that the distribution of current in the branches or derived circuits may be always uniform, and also to provide a final cut-out for closing a circuit of low resistance around a group of derived circuits when all the lamps of such group have been extinguished. The general plan by which I accomplish this result is by the employment with each group of lamps of a supplemental circuit, including an electro-magnetic circuit-controller, and having as many breaks as there are lamps in the group. Normally these breaks are all open when the lamps are running; but on extinguishing a lamp the device that is operated for that purpose or operated

thereby closes one of the breaks in the supplemental or controlling circuit. The supplemental circuit, however, will not be completed until all the breaks are closed, or, what is the same thing, until all the lamps are extinguished. When the last lamp is withdrawn, the completion of the supplemental circuit energizes an electro-magnet, which operates an armature and closes a shunt or branch of low resistance around the whole group of lamps and resistances. The supplemental or controlling circuit may be independent of the lighting circuit or derived therefrom. In the former case it is necessary to employ a small battery to furnish the requisite current, and in the latter to use some means for preventing the vibration of armature of the electro-magnetic switch. The controlling-circuit may also be arranged in different ways with reference to the lamps or their controlling devices. For instance, the breaks may all be in the main controlling-circuit—that is to say, in series—or, with slight changes in the mode of operation of the circuit closers or switches, they may be in cross or branch circuits between the positive and negative wires of the controlling-circuit.

In my present application I will describe the former arrangement, the other being made the subject of a separate application. The details of the system will be described by reference to the accompanying drawings, in which—

Figure 1 is a diagram of the system, showing the use of an independent controlling-circuit; Fig. 2, a diagram of the same, with a controlling-circuit in derivation to the main.

Let A designate the conductor of a main line; B, a given number of divisions of such line brought into derivation or multiple arc, and united to the main line by the conductors C C.

In each branch or division B is included an electric incandescent lamp, D, or some similar translating device, this being a well-known modification of the plan or system for distributing current known as "multiple arc." In each branch B is also an electro-magnetic cut-out, E, and a break, F. Around each lamp and break is a resistance-circuit, G, containing a resistance-coil, R, equivalent to one lamp,

and connected with and controlled by the cut-out E, the object being to provide an automatic device for substituting a resistance for a lamp, whether the lamp be extinguished by hand or by the destruction of its carbon.

H designates switches, to be operated manually, for the purpose of controlling the breaks in the branches B.

K is the supplemental or controlling circuit, 10 containing an electro-magnet, L, and breaks M, the wire of the circuit K being carried around to each switch H, and the breaks therein located in proximity to those in the branches B, so that the same switches control both—that is to say, when a switch is turned to open 15 a branch circuit, it closes one of the breaks in the controlling-circuit, and conversely.

In Fig. 1 a small battery, N, is shown in the controlling-circuit K.

20 The electro-magnet L is provided with a pivoted armature-lever, l, that forms the contact-lever of a switch in a shunt-circuit, O, of low resistance around the entire group of derived circuits and all the devices included therein. If all the breaks M in circuit K are closed, which will be the case when all the lamps are extinguished, the circuit is complete, and the electro-magnet L is rendered active. This closes circuit O and shunts the current 25 around the group of lamps and resistances. If then any one or more of the switches be turned to bring in a lamp or lamps, the circuit K is again broken and the current passes through the active lamps and the resistance-coils of those not brought into circuit.

30 In Fig. 2 the circuit K is derived from the main line and contains no battery. In this case I have shown as a means of preventing the vibration of the contact-lever of the electro-magnet the following: a spring-impelled contact-lever, m, and a pivoted armature-lever, n, with a catch, n', that engages with the lever m and holds it out of contact with its stop. When the magnet L is energized, the 40 lever m is set free and closes the circuit O. With this arrangement it is necessary to break the circuit K by hand when lamps are brought into the circuit. This is, however, but one of a number of expedients that may be resorted to for accomplishing the end desired.

45 In carrying out my invention I may use a great variety of mechanical devices operating on the general principle herein described. The control of the circuit K may, for example, be effected, not only by the manual switches, but by the automatic switches or cut-outs, as will be readily seen by reference to the patents above mentioned, and in other respects the system may be modified within the limits of my invention.

50 In practice, a number of the groups of derived circuits described are formed in series in the circuit A, and some means used to regulate the current generated, so that a uniform flow of current will be maintained.

It is possible to run more than one lamp in each branch by duplicating the devices described, and by making such other obvious changes as the circumstances of the case require.

70 What I claim is—

1. The combination, with a divided main line, incandescent lamps, switches, and resistances to be substituted for the lamps included in or connected with the divisions or branches of the circuit, of a shunt of low resistance around the divisions of the circuit, a supplemental circuit controlled by the lamp-switches, and a switch in the shunt of low resistance controlled by a magnet in the supplemental circuit, as set forth.

2. In a multiple-series system in which the line is divided at intervals into a group or given number of branches, the combination, with each branch in a group, of an incandescent lamp, a manual switch, a resistance, and an automatic switch or cut-out for introducing the resistance in place of the lamp, and with the entire group of branches, of a shunt of low resistance, a supplemental circuit controlled by the lamp-switches, and an electro-magnet and devices operated thereby for controlling the shunt of low resistance, as and for the purpose set forth.

3. In a multiple-series system in which the line is divided at intervals into a group or given number of branches, the combination, with each branch in a group, of an incandescent lamp, a manual switch, a resistance, and an automatic switch or cut-out for introducing the resistance in place of the lamp, and with the entire group of branches, of a shunt of low resistance, a supplementary circuit containing a series of breaks that are opened by the movements of the lamp-switches and interrupt the lamp-circuits, and conversely, an electro-magnet in said supplemental circuit, and switch mechanism in the shunt of low resistance operated thereby, as set forth.

4. In a multiple-series system in which the line is divided at intervals into a group or given number of branches, the combination, with each branch in a group, of an incandescent lamp, a manual switch, a resistance, and an automatic switch or cut-out for introducing the same in place of the lamp, and with the entire group of branches, of a shunt of low resistance, an independent circuit containing a series of breaks that are opened and closed by the movements of the lamp-switches, a battery and electro-magnet in the independent circuit, and switch mechanism in the shunt operated or controlled thereby, as and for the purpose set forth.

5. In testimony whereof I have hereunto set my hand this 25th day of November, 1884.

EDWARD WESTON.
